United States Patent Office

Des. 181,761
Patented Dec. 17, 1957

181,761

BOOT

Myrtle E. Thielen, Long Beach, Calif.

Application July 8, 1957, Serial No. 46,859

Term of patent 14 years

(Cl. D7—4)

FIG. 1.

FIG. 2.

FIG. 3.

FIG. 5.

FIG. 4.

FIG. 6.

I claim:

The ornamental design for a boot, substantially as shown.
